UNITED STATES PATENT OFFICE.

CHARLES L. CAMPBELL, OF OAKS, PENNSYLVANIA, ASSIGNOR TO JOHN C. DETTRA & COMPANY, INC., OF OAKS, PENNSYLVANIA, A CORPORATION OF PENNSYLVANIA.

DESIGN FOR A PENNANT.

50,413.

Specification for Design.

Patented Mar. 6, 1917.

Application filed December 13, 1916. Serial No. 136,795. Term of patent 7 years.

To all whom it may concern:

Be it known that I, CHARLES L. CAMPBELL, a citizen of the United States, residing at Oaks, in the county of Montgomery and State of Pennsylvania, have invented a new, original, and ornamental Design for Pennants, of which the following is a specification, reference being had to the accompanying drawing, forming a part thereof.

The figure is a side elevation of a pennant showing my new design.

I claim:

The ornamental design for a pennant as shown.

CHARLES L. CAMPBELL.

Witnesses:

CLYDE I. FREECE,
EDNA FAMOUS.
